UNITED STATES PATENT OFFICE.

MALCOLM B. MOYER, OF MONTEVIDEO, MINNESOTA.

TRACK-HANGER.

1,165,699.

Specification of Letters Patent. Patented Dec. 28, 1915.

Application filed May 13, 1915. Serial No. 27,384.

To all whom it may concern:

Be it known that I, MALCOLM B. MOYER, a citizen of the United States, residing at Montevideo, in the county of Chippewa and State of Minnesota, have invented certain new and useful Improvements in Track-Hangers; and I do declare the following to be a full, clear, and exact description of the invention, such as will enable others skilled in the art to which it appertains to make and use the same.

This invention relates to improvements in hangers and more particularly to track hangers for elevated rails.

15 The object of the invention is to provide a hanger of this character so constructed that after the rail has been mounted therein, a tight fit may be insured without the use of any bolts or screws.

20 Another object is to provide a hanger so constructed which permits rapidity of erection, takes care of the irregularity in the thickness of the shapes as they come from the mill and at the same time provides ready 25 means for tightening the grip on the track when installation is to be made.

With these and other objects in view, the invention consists of certain novel features of construction, and the combination and arrangement of parts as will be more fully described and claimed.

In the accompanying drawings: Figure 1 represents a front elevation illustrating a rail supported by hangers constructed in accordance with this invention; Fig. 2 is a side elevation of one of the hangers showing the rail and the supporting joist in transverse section; Fig. 3 is a rear elevation of the hanger applied; Fig. 4 is a transverse section taken on the line 4—4 of Fig. 2 showing the gripping action of the hanger on the rail; Fig. 5 is a side elevation of the hanger showing another form of connecting it with its support; Fig. 6 is a rear elevation thereof; Fig. 7 is a detail perspective view of the extension clip, and Fig. 8 is a similar view of the nailing plate.

In the embodiment illustrated in Figs. 1 to 4, a pair of hangers 1 constructed in accordance with this invention are shown for

supporting a rail R, it of course being understood that any desired number of such hangers may be employed according to the length of the rail to be supported and all being exactly alike, hence only one will be 55 described in detail. Each of these hangers 1 as shown is constructed of two members 2 and 3 which are exactly alike in shape and size and have a general semi-elliptical contour. At the upper end of the body portion 60 of each of the members 2 and 3 is formed a head 4 provided with a plurality of apertures 5 for the passage of suitable fastening bolts whereby the hangers may be secured to a suitable overhead support here shown 65 in the form of a joist J. To adapt these hangers to be connected with the joist J so that the rail R supported thereby will extend parallel with the joist, nailing plates 5' are provided which are here shown in the 70 form of right angular members having one arm 6 thereof secured to the joist J by suitable bolts and the other arm 7 provided with a plurality of bolt openings 7' positioned to register with the apertures 5 in the head 4 75 so that when the parts are assembled the fastening bolts which connect the hanger to the plate will pass through the registering apertures in said head and the arm 7 of the plate, said plate arm 7 being shown disposed 80 between the members 2 and 3 of the hanger 1 and reliably clamped therebetween. These members 2 and 3 are bolted together intermediately of their ends preferably midway 85 their length and have a spacing element 8 arranged between them as is shown clearly in Fig. 3. The body portions of the hanger members 2 and 3 are provided at their lower ends with laterally extending arms 10 each of which is provided with a rail seat 11, the 90 seat in one member registering with that in the other, said seats being here shown substantially L-shaped in cross section with the mouths thereof opening upwardly as is shown clearly in Fig. 2. While these seats 95 are shown substantially L-shaped to receive channel iron rails it is obvious that they may be made inverted T-shaped when I beams are to be supported thereby. The arms 10 of these members 2 and 3 are de- 100

signed to be bent laterally outward away from each other to form between them a substantially V-shaped space 12, and when the rail is applied, these arms are pressed 5 toward each other into substantially parallel relation and the rail is slipped longitudinally into the seats 11, and on the release of said arms 10 they will spring outwardly into their normal position shown in Fig. 4, therefore 10 by causing the seats 11 to engage the opposite faces of the rail web at diagonally opposite points, thereby insuring a firm gripping action of the arms on the rail, it being obvious that when so held, no bolts or other 15 fastening elements are required for securing the rail to the hangers and to prevent longitudinal movement thereof.

In the form shown in Figs. 5 to 8, the hanger proper 1 is shown constructed the same as that of the other figures, the connection between said hanger and the supporting joist J being different, the hanger of these figures being designed for disposition in a plane considerably below the joist 25 on which it is mounted and is so mounted to provide for the placing of the track to allow the carrier wheels which travel thereon to clear the joist J. The connections for the hangers which are designed to be so positioned are here shown in the form of bolts 13 adjustably mounted at their upper ends in the laterally extending arm 7^a of a nailing plate 5^a which is similar in construction to the nailing plate 5' of the 30 other figures except that the arm or wing 7^a thereof is disposed in a horizontal position and is provided with an opening 14 through which the bolt 13 passes, said bolt being held in adjusted position in said opening by means of two nuts 15 and 16 arranged on opposite sides of the arm 7^a. A clip 17 here shown U-shaped in construction has bolt openings 18 in the legs thereof through which the bolt 13 is designed to 35 pass, the cross bar 19 of said clip being bolted to the head 4 of the hanger 1 in a manner similar to that in which the nailing plate 5' of the other figures is secured thereto. This clip 17 is held in adjusted position on the bolt by suitable nuts 20 and 21 arranged on said bolt on the outer faces of the legs of the clip as is shown clearly 40 in Fig. 5, and by means of which said clip and the hanger carried thereby may be adjusted to raise or lower it in relation to the joist J and thus provide for the proper clearance of the wheels of the carrier carried on the track R supported by said hangers.

60 In assembling these hangers 1, the arms 10 of each hanger are pressed toward each other and are slipped on the end of the rail R and are then fastened in position on the rail by releasing the arms 10 after said

hangers have been properly positioned on the rail. The angular shape of the rail seats serves to hold the rail or rails against any possible vertical movement and the gripping action of the diagonally opposite edges of the seats of the rail R when the arms 10 are sprung apart serves to hold the rail against longitudinal movement.

I claim as my invention:

1. A track hanger comprising a substantially elliptical member having laterally extending parallel arms at one end diverging toward their free ends and provided with upwardly opening rail receiving seats, and means at the other end thereof for connecting the hanger to a support. 75

2. A track hanger comprising an upright body portion having laterally extending parallel arms provided with means for gripping the rail web when the parts are assembled. 80

3. A track rail comprising an upright member having laterally extending parallel arms provided with registering rail receiving seats, said seats having gripping means for tightly engaging and holding the opposite sides of the rail web. 85

4. A track hanger comprising an upright member having laterally extending parallel arms with registering rail receiving seats therein, said seats being provided with diagonally disposed rail gripping elements. 90

5. A track hanger comprising an upright member having laterally extending laterally spreadable arms provided with registering rail seats. 95

6. A track hanger comprising an upright body portion having a laterally extending rail carrying member at one end and an attaching head at the other end, an angular plate adjustably connected with said head, and means for connecting said plate to a support. 100

7. A track hanger comprising an upright body portion having a laterally extending rail carrying member at one end and an attaching head at the other end, an angular attaching plate having a bolt opening in one member thereof, a clip secured to the head of said hanger and provided with laterally extending apertured arms, and a bolt extending through the apertured member of the attaching plate and the arms of said clip and provided with means for adjustably connecting said clip and plate therewith. 110

8. A track hanger comprising an upright member having a laterally extending track receiving element at one end and an attaching head at its other end, a U-shaped clip with the cross bar thereof secured to said attaching head and its arms extending laterally outward from said head in the same direction and arranged in vertical alinement, said arms being provided with bolt receiving apertures, an angular plate for connec- 115 120 125

tion with a support having a bolt aperture in one arm thereof and a bolt extending through said attaching plate and the arms of said clip, and nuts mounted on said bolt for adjustably connecting the hanger thereto and the bolt to the plate.

In testimony whereof I have hereunto set

my hand in presence of two subscribing witnesses.

MALCOLM B. MOYER.
